PLATE CLAMPING MECHANISM

Albert J. Horton, White Plains, N. Y., assignor
to R. Hoe & Co., Inc., New York, N. Y., a cor-
poration of New York

Application June 2, 1937, Serial No. 145,964

16 Claims. (Cl. 101—378)

This invention relates to plate clamping means for printing and like machines, and more particularly to clamping mechanism for engaging the straight edges of plates used for printing newspapers and similar matter that is printed at high speed.

The plate clamping mechanism of this invention is particularly adapted and arranged to engage the straight edges of a precurved plate mounted upon a form cylinder of a printing machine and hold it closely thereagainst to prevent these edges from bowing outwardly away from the cylinder, due to centrifugal force, or other causes. The clamping mechanism herein disclosed includes a movable member, forming part of a margin bar for the straight edge of a curved printing plate, and having an edge adapted to overhang the straight edge to engage the same, biasing means adapted to constantly urge the member into engagement with the edge, and one or more fixed members adapted to engage and hold the opposite straight edge of the plate.

One object of this invention is to provide an improved plate clamping mechanism of the above nature.

Another object is to provide in plate clamping mechanism of the above nature, a member in engagement with a straight edge of a curved plate, biasing means arranged to constantly urge the member into such engagement with the plate, whereby the plate will be held firmly against the surface of the cylinder upon which it is mounted, and a fixed member against which the opposite edge of the plate abuts.

Another object is to provide a plate clamping mechanism having a biased movable member and a fixed member arranged to engage opposite straight edges of a curved plate on a form cylinder and including the feature that the biased movable member is reversible in accordance with the direction of rotation of the cylinder.

It is also an object of this invention to provide a plate clamping mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

Two embodiments of this invention are illustrated in the accompanying drawings, wherein:

Figure 1 is a face view of a form cylinder of a printing machine, with plate clamping means embodying the features and principles of this invention associated therewith;

Figure 2 is an enlarged cross-section of the cylinder taken on line 2—2 of Figure 1;

Figure 3 is an enlarged broken plan view of the movable and fixed plate clamping members;

Figure 4 is a section taken on line 4—4 of Figure 3;

Figure 5 is a section taken on line 5—5 of Figure 3;

Figure 6 is a longitudinal section taken on line 6—6 of Figure 3;

Figure 7 is an enlarged cross-section of the cylinder shown in Figure 1 and showing a somewhat modified form of plate clamping mechanism;

Figure 8 is an enlarged broken plan view of the movable and fixed plate clamping members of the form shown in Figure 7;

Figure 9 is a section taken on line 9—9 of Figure 8; and

Figure 10 is a longitudinal section taken on line 10—10 of Figure 8.

The features and principles of this invention being especially adapted for association with the form cylinder of a printing machine, the drawings illustrate a form cylinder 11 having shaft ends 12 and 13 extending from its ends whereby it may be journaled in suitable supports (not shown) and be rotated to perform its usual function in combination with the other mechanism of the printing machine. The cylinder 11 as shown, is adapted to have a plurality of stereotype or other precurved, substantially semi-cylindrical printing plates 14 mounted thereon and is provided with the usual curved edge clamping and locating members 15. The plates 14 generally extend peripherally about the cylinder 11 and have the straight edges 16 and 17 of one plate spaced from, and in opposed relation to, the edges 16 and 17 of another plate.

The clamping members 15 impose a cross pressure upon the plates 14 and the rapid rotation of the cylinder 11 develops centrifugal force, both of which forces tend to bulge the section of the plate 14 between its curved edges 18 and 19 away from the cylinder. This bulging tendency is greatest at the center of the straight edges 16 and 17 of the plates 14, for the central portions 21 of the plate are inherently stiffened due to their arcuate form. This invention provides means to counteract this bulging tendency by the provision of a fixed plate edge engaging

- member, or members 22, and a biased movable plate edge engaging member 23 adapted to respectively engage the opposite straight edges 16 and 17 of the plate 14.
- 5 The fixed members 22 have their base portion 24 disposed in diametrically opposite longitudinally extending slots 25 formed in the periphery of the cylinder 11 between the spaced apart straight edges 16 and 17. The head portion of 10 each member 22 has a flange 26 extending laterally from one edge thereof and which is adapted to overlie one of a pair of shoulders 27 and 28 formed respectively on the straight edges 16 and 17 of each plate. The members 22 are fixedly secured to the cylinder 11 by screws 29 and 15 with the movable members 23 provide a margin bar arrangement between the opposing plate edges 16 and 17. The abutting surfaces 31 and 32 of the shoulder 27 or 28 and the flange 26 respectively are slightly inclined whereby should they be pressed toward each other, the contact therebetween will increasingly tighten.
- In the form shown in Figures 2-6 inclusive, 20 the movable members 23 have a base portion 33, and a flange 34 extends laterally from an upper edge of the base portion in position to overlie one of the pair of shoulders 27 and 28 of the plates 14, the surface 35 abutting the shoulder surface of the respective edge being correspondingly inclined. The base portions 33 of diametrically opposite members extend into the respective slots 25 in the cylinder 11 and are slightly narrower in width than the width of the slot. A pair of rods 36 are secured at each of their ends to each 25 of the members 23 by a screw 37 and pass through a hole 38 formed in the cylinder 11, the holes 38 being of larger diameter than the rods 36 and extending from and between the diametrically opposite slots 25.
- 30 The flange 34 of opposite movable members 23 are shown in position to overlie the shoulder 28 of opposite plates respectively and are constantly biased toward the respective plate straight edge 17 by springs 39 disposed in counterbores 41 formed in the side surface 42 of the base portion 33. The springs 39 react between the bottom of the counterbores 41 and the adjacent side surface 43 of the slot 25. In order to obtain the results desired, the members 23 are assembled in 40 the cylinder 11 with their flanges 34 directed reversely to the direction of rotation of the cylinder, as shown in Figure 2, so that the springs 39 will bias the flanges 34 circumferentially about the cylinder 11 over the shoulders 28.
- 45 It will be observed from the arrow in Figure 2 which indicates the direction of rotation, that the arrangement is such that the leading edge of each plate is engaged preferably by a movable clamping member, and the trailing edge by fixed 50 clamping members. When a plate is placed on the cylinder, the spring pressure exerted by the movable clamping member tends to push the plate around the cylinder into firm engagement with the fixed clamping member. Furthermore, 55 when the machine is started and the printing plate engages the impression cylinder, the rolling motion under ordinary conditions, also tends to move the plate backward on the cylinder and into engagement with the stationary clamping members. Due to the cooperating inclined surfaces 60 on the plate and on the clamping members, both straight edges of the plate will thus be constantly urged against the cylinder 11 and prevented from bowing outward when rotated at high speed.
- 70 When it is desired to reverse the direction of

rotation of the cylinder, the members 22 and 23 are disconnected from the cylinder and the rods 37 respectively, and removed from the slots 25 and reversed, to direct the plate engaging flanges of each member so that the flange 26 on the fixed 5 member 22 will be directed with, and the flange 34 of the movable member 23 will be directed reversely to, the desired direction of cylinder rotation.

In the form shown in Figures 7-10 inclusive, 10 the straight edge clamping members 47 and 48 corresponding to the members 22 and 23 respectively of the previously described form, are each provided with flanges on both sides to simplify the operation of preparing the cylinder for rotation in the opposite direction. The fixed members 47 are provided with oppositely directed flanges 49 and 51 and the movable plate engaging members 48 are provided with oppositely disposed flanges 52 and 53 and are joined together 20 by rods 54 which correspond to the rods 36 of the form previously described.

The base portion 55 of each member 48 is cut away to provide a transverse slot 56 therethrough in which oppositely facing bowed leaf springs 57 25 and 58 are disposed, the ends of which springs engage the opposite side faces 59 and 61 of the slots 25 in the cylinder 11. The springs 57 and 58 at their central portion 62 engage a post 63 which is provided with cylindrical ends 64 and 65, rotatably supported in the member 48 above and below the slot 56. The upper end 64 is provided with a cross slot 66 into which a tool may be inserted by which the post 63 may be turned. The post 63 is provided with opposite flattened 30 sides 67 and 68 that are engaged by the springs 57 and 58 respectively, and which are arranged at differing radial distances from the axis of the cylindrical ends 64 and 65. The surface 67, being at the greater radial distance, compresses 40 the spring 57, as shown in Figure 8, and biases the member 48 downward, and the flattened side 67 prevents the post from being inadvertently turned.

Whenever it is desired to reverse the direction 45 of rotation of the cylinder, the members 48 need not be disconnected from the rods 54 in order to reverse the direction in which the members are biased, as required in the previous form in respect to the members 23, and the members 47 50 need not be removed from the cylinder and reversed as required of the members 22. In this form, all that it is necessary to do in order to reverse the direction in which the members 48 are biased, so that it will be reverse to the direction of rotation of the cylinder 11, is to turn the post 63 so that the proper spring 57 or 58 is compressed and tensioned. When one spring 57 or 58 is made operative by being so compressed and tensioned, the other is relieved of tension 60 and is therefore inoperative. Indicating marks 69, which will cooperate with the slot 66 to simulate an arrow as shown in Figure 8, may be provided on the upper end of the post 63 to indicate, by pointing in the direction of the rotation of 65 the cylinder, which spring 57 or 58 is in operative position. In all other respects, the members 48 operate in cooperation with the fixed members 47 as do the members 23 in respect to the members 22 of the first described form.

Obviously the invention may be applied to cylinders adapted to receive other than semi-cylindrical plates; as for instance, arrangements in which there are four plates in line around the cylinder.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the means herein disclosed forms a part of the invention included in this application.

What I claim is:

1. In a plate clamping mechanism adapted to engage the straight edges of a pair of substantially cylindrical plates to hold the plates firmly against the surface of a cylinder, a pair of fixed members spaced apart circumferentially of the cylinder, one clampingly engaging one straight edge of each plate, a pair of movable members spaced apart circumferentially of the cylinder, one clampingly engaging the other straight edge of each plate, means passing through the cylinder to connect said movable members, and means to bias each of the movable members to constantly urge them circumferentially about the cylinder and into engagement with the plate.

2. In a form cylinder for a printing machine adapted to print from precured printing plates, plate clamps adapted to engage the curved edges of the plate, a fixed clamp adapted to engage a straight edge of the plate, a movable clamp adapted to engage the opposite straight edge of the plate, and selective biasing means to urge the movable clamp circumferentially about the cylinder in either direction.

3. In a plate clamping mechanism for a form cylinder, a pair of movable clamps, one clamp being adapted to engage the leading straight edge of one of two oppositely disposed plates on said cylinder, and the other clamp being adapted to engage the leading straight edge of the other plate, a member connecting said clamps together, and means to bias each clamp circumferentially about the cylinder toward the leading edge engaged thereby.

4. In a plate clamping mechanism for holding curved plates on a cylinder, a member mounted on the cylinder between adjacent straight edges of adjacent plates for movement circumferentially about the cylinder in either direction, and means arranged to be selectively tensioned to bias the member in either direction of its movement.

5. In a plate clamping mechanism for the straight edges of a pair of curved plates on and spaced about a cylinder, a fixed stop for one straight edge of each plate, movable clamping members each having a flange adapted to overlie a portion of the other straight edge of each plate, a member connecting said movable members, and means to bias each of said clamping members toward the straight edge said flange of each member overlies.

6. In a plate clamping mechanism for the straight edges of a pair of curved plates on and spaced about a cylinder, a fixed stop for one straight edge of each plate, movable clamping members each having a flange adapted to overlie a portion of the other straight edge of each plate, cooperating inclined surfaces between each of the flanges and the underlying portion of the plate edge whereby the plate edge will be forced toward the cylinder surface when the clamping member is moved toward the edge, a member connecting said movable members, and means to bias each of said clamping members toward the straight edge said flange of each member overlies.

7. In a plate clamping mechanism for the adjacent spaced apart straight edges of a pair of precured plates on a cylinder, a fixed stop disposed between the adjacent straight edges, a movable clamping member disposed between and having flanges adapted to overlie a portion of the adjacent straight edges, and means adapted to be brought into operative condition to selectively bias said clamping member toward either of the adjacent plate edges.

8. In combination, a cylinder, a pair of substantially semi-cylindrical precured plates on said cylinder with their adjacent straight edges spaced apart on opposite sides of the cylinder, a fixed clamping member between each pair of spaced apart straight edges and adapted to engage the trailing edge of one plate, a movable clamping member between each pair of spaced apart straight edges, each of said movable members having a flange adapted to engagingly overlie a portion of the leading edge of a plate, the trailing edge of which is engaged by the fixed clamp on the opposite side of the cylinder, a member passing through the cylinder transversely to the axis thereof and connecting said movable members, and means to bias said movable members to force said flanges thereon into engagement with the plate edges which they overlie.

9. In combination, a cylinder, substantially semi-cylindrical precured plates on said cylinder with their adjacent straight edges spaced apart on opposite sides of the cylinder, a fixed clamping member between each pair of spaced apart straight edges and adapted to engage the same, a movable clamping member between each pair of spaced apart straight edges, each of said movable clamping members having oppositely directed flanges adapted to overlie a portion of the adjacent edges of the plates, a member passing through the cylinder and connecting the said movable clamping members, and means to bias said movable members to selectively force the flanges into engagement with a plate edge.

10. In a plate clamping mechanism, a movable plate clamp adapted to be disposed between spaced apart plate edges and to be selectively moved into engagement with each edge, springs oppositely operative to bias the clamp toward each edge, and means to selectively make one of said springs operative and the other inoperative.

11. In a form cylinder for a printing machine adapted to print from a pair of substantially semi-cylindrical printing plates disposed circumferentially about the cylinder, longitudinally movable plate clamps adapted to engage the curved edges of each plate, fixed clamps each adapted to engage a first straight edge of one of said plates and connected clamps movable circumferentially of said cylinder each adapted to engage a second straight edge of one of said plates and resiliently biased into engagement therewith.

12. In a form cylinder for a printing machine adapted to print from a pair of substantially semi-cylindrical printing plates disposed circumferentially about the cylinder, longitudinally movable plate clamps adapted to engage the curved edges of each plate, fixed clamps each adapted to engage a first straight edge of a plate, a pair of connected clamps movable on said cylinder on an arc substantially parallel to the circumference thereof, each clamp being adapted to engage a second straight edge of a plate, and resilient means to bias the movable clamps cir-

cumferentially about the cylinder and against the straight edges of the plates.

13. In a plate clamping mechanism adapted to engage the straight edges of curved printing plates oppositely disposed about and mounted on a cylinder and hold the same thereon, a plate edge engaging member for one of the straight edges of each plate, means passing through the cylinder transversely of its axis to connect the members engaging the edges of different plates, means to resiliently urge said members into plate edge engagement, and means fixed to the cylinder to engage the other edge of each plate.

14. In a clamping mechanism adapted to engage the straight edges of curved printing plates oppositely disposed about and mounted on a cylinder and hold the same thereon, a plate edge engaging member for one of the straight edges of each plate, a rod passing through the cylinder and having one of said members detachably secured thereto at each of its ends to connect the members together, means resiliently acting against each member to urge it into plate edge

engagement, and means fixed to the cylinder to engage the other edge of each plate.

15. In a plate clamping mechanism for holding curved plates on a cylinder, a pair of members each mounted on the cylinder and movable on an arc substantially parallel to the circumference of the cylinder into engagement with a plate edge, means to bias the members toward plate engaging position, and means extending transversely through the cylinder and connecting said members together.

16. In a plate clamping mechanism for holding curved plates on a cylinder, a pair of members fixed on said cylinder to engage the trailing edges of a pair of plates, a pair of members each mounted on the cylinder and movable on an arc substantially parallel to the circumference of the cylinder into engagement with the leading edges of the plates, rods extending transversely through the cylinder and connecting said movable members, and means to bias said movable members to clamp the plates.

ALBERT J. HORTON.
